COMBINED DISPLAY PACKAGE AND CARRIER FOR DISHES OR SIMILAR ARTICLE

David J. Freiman, Corning, N.Y., assignor to Corning
Glass Works, Corning, N.Y., a corporation of New York

Filed Dec. 26, 1967, Ser. No. 9,919

Term of patent 14 years

Int. Cl. D9—04

U.S. Cl. D9—191

Fig. 1

Fig. 2

Fig. 3

Fig. 4

Fig. 5

FIG. 1 is a front elevational view of a combined display package and carrier for dishes or similar article showing my new design;

FIG. 2 is a rear elevational view;

FIG. 3 is a side elevational view;

FIG. 4 is a top plan view; and

FIG. 5 is a bottom plan view.

I claim:

The ornamental design for a combined display package and carrier for dishes or similar article, as shown and described.
